UNITED STATES PATENT OFFICE.

LOUIS J. WILLARD, OF NORWALK, OHIO, ASSIGNOR TO THE ROTARY PRINTING COMPANY, OF NORWALK, OHIO, A CORPORATION OF OHIO.

PERFORATING DEVICE.

Application filed August 28, 1925. Serial No. 52,994.

This invention relates to sheet perforating mechanism particularly adapted to paper sheets, and the primary object is to provide a mechanism adapted to operate on a moving sheet or strip of paper, for example as fed from a web printing press, and effectively perforate such sheet.

Another object is to provide a simple effective perforating apparatus which may be mounted in a convenient manner in a pair of rolls capable of feeding the sheet and place the perforations in predetermined positions on the sheet.

A further specific object is to provide a simple device for arranging a plurality of perforating devices in a pair of coacting rolls in such a manner that their relative position on the respective rolls may be easily changed.

20 I have discovered that I can accomplish the desired result by mounting in a pair of coacting rolls capable of feeding paper sheets, a pair of elements comprising simply a hollow die carried by one of the rolls, and 25 a spherical die member resiliently carried by the other roll and adapted to register with the hollow die. I find that the same spherical member may be used with hollow dies of various sizes.

30 Further features of the invention will appear in the following description which relates to the accompanying drawing. The essential novel characteristics will be summarized in the claims.

35 In the drawings, Fig. 1 is a perspective view of a pair of coacting rolls in which my invention is embodied; Fig. 2 is a cross section through a single perforating unit; Fig. 3 is a perspective view of a preferred form 40 of female die; Fig. 4 is a perspective view of a sheet as perforated by the arrangement shown in Fig. 1.

45 In the embodiment shown, the mechanism is arranged to perforate sheets or a web of fed paper with a series of aligned holes, such as commonly used for loose-leaf binder sheets.

50 Referring in detail to the drawings and indicating the various parts by suitable characters, the male die elements, including the respective holders therefor, are indicated generally at 1 and the female die elements at 2, each set being suitably mounted in

respective rolls R and R'. Each male die element as shown in Fig. 2 comprises a spherical punch or perforator, preferably a metal ball 3 which may be mounted in a cylindrical shell or holder 4 having an inturned portion 5 for retaining the ball within the shell. Arranged to urge the ball outwardly against this inturned portion I have shown a spring 6 bearing against a washer 7 having a concave lower surface adapted to engage the ball.

55 Suitable means for adjusting the action of the spring may comprise a threaded plug 8 bearing downwardly upon the upper end of the spring as shown and threaded into the shell. The shell as shown is threaded externally throughout the greater part of its length as at 10 into a block 11 which block may be made with a dove-tail shank adapted to enter T-slots 13 which I have shown conveniently arranged in the body of each of the rolls. Any suitable means may be provided for holding the shell in adjusted position so that the ball is maintained in proper relation to the peripheral surface of its roll, such for instance, as a set-screw 15 in the body of the block 11.

60 The female dies comprise essentially members such as indicated at 20 each having a circular cutting edge as shown at 21. Each die 20 as shown has a central longitudinal flaring opening 22 which widens toward the axis of the roll upon which it is mounted in order to provide for the easy discharge of scrap paper therethrough into the interior 65 of the roll.

65 The female die may be held in a manner similar to that of the shell 4, namely by means of being threaded as at 24 into a block 25 where it may be held by a set-screw 15'. Any suitable means may be provided effecting longitudinal adjustment of both the shell 4 and die 20, such for instance, as screw-driver slots 26 and 27 in the shell and die respectively.

70 The block 11 and 25 may be slidably mounted in T-slots as shown in Fig. 1 and metal inserts such as indicated at 28 may serve to position the blocks, longer or shorter inserts being employed where it is desired to vary the distance between the perforations in the paper. Suitable means may be provided to prevent the blocks and inserts from

shifting lengthwise of the rolls. I have shown, for instance, a split block 30 mounted in the groove, and expandable by means of a screw 31 passing into a tapered thread in the block.

I have found that when such an arrangement is mounted as just described, in suitable rolls, that a single set of balls may be employed with a number of female dies each 10 of which has a cutting edge of different diameter, it being simply necessary to adjust the ball or die up or down as required in such a manner that the ball seats firmly against the edges of the die when paper is 15 fed therebetween.

It will be seen that when a web or sheet of paper such as indicated at S is being fed, as from a printing press, into the bite of the rolls R and R', the paper as it passes between the balls and dies will be cut by the 20 engaging surfaces thereof to form lines of perforations such as shown at P in Fig. 4.

I have found that with the hollow dies and the cooperating spring pressed balls as 25 herein explained, I obtain very effective perforations notwithstanding the paper travels at a high speed between the rolls. The perforations are accurately made, and there is no tendency to tear or mar the paper. Various sizes of hollow dies will cooperate 30 satisfactorily with the same balls. As illustrated in the drawings, the perforating devices may be grouped on the rolls in any arrangement desired. It should be understood however, that I do not limit myself to any particular arrangement for mounting the die elements in the rolls.

Having thus described my invention, I claim:

40 1. The combination of a pair of rolls each equipped with undercut grooves in its surface, blocks adjustably mounted in said

grooves to occupy various positions in the rolls, hollow dies mounted in the blocks of one roll in a manner to enable them to be 45 adjusted radially, and resiliently supported hollow spherical punches mounted in the blocks of the other roll and adjustable radially therein.

2. In combination with a pair of coacting rolls, a die having an abrupt circular cutting edge arranged to be carried by one of the rolls, a die having a spherical cutting surface resiliently mounted and arranged to be carried by the other roll, each of said dies having a screw threaded mounting in its roll whereby there is provided means for positioning each of said dies on their respective rolls at various positions relative to the peripheral surface of such rolls and in registration with each other.

3. In combination, a female die having a circular cutting edge, means for mounting the die, means whereby the die may be turned to adjust it and means for holding 65 the die in adjusted position, a spherical die member arranged to register with the said cutting edge, means including a threaded sleeve for supporting the spherical die member, and means for turning the sleeve to effect adjustment thereof relative to the female die.

4. The combination of a pair of rolls each having a plurality of longitudinal grooves in its surface, blocks adjustably positioned 75 in the respective grooves, hollow dies screw threaded radially in the blocks in one roll, hollow casings screw threaded radially in the blocks of the other roll, a ball in each casing and a spring in each casing pressing 80 the ball outwardly.

In testimony whereof, I hereunto affix my signature.

LOUIS J. WILLARD.
